United States Patent Office.

DAVID MANUEL, OF BOSTON, MASSACHUSETTS, ASSIGNOR TO HIMSELF
AND WILLARD MANUEL, OF SAME PLACE.

Letters Patent No. 74,233, dated February 11, 1868; antedated January 24, 1868.

IMPROVED MACHINE FOR MAKING WIRE SPRINGS.

The Schedule referred to in these Letters Patent and making part of the same.

TO WHOM IT MAY CONCERN:

Be it known that I, DAVID MANUEL, of Boston, State of Massachusetts, have invented new and useful Improvements in Machines for Forming Wire Springs; and I do hereby declare the following to be a full and exact description of the same, reference being had to the drawings that accompany and form a part of these specifications, in which—

Figure 1 is a perspective view of the machine.

Figure 2, detached parts of the portion of the machine to which my invention relates.

Figure 3, view of a spring formed for spring-bed or upholstering purposes.

Letter A, the form on which the spring is wound; letter B, portion of a hollow spire spindle; letter C, the counterpart to B; letter D, a strong thimble, which is made to embrace B and C, as illustrated in Figure 4; letter E, a spiral spring, holding the form A in place; letter F, a spring formed for bed-bottom or upholstering purposes; letter *h*, a hollow, formed partly in B and partly in C; letter *i*, tongue of the spring F, which lies in the hollow cylindrical bore of B and C, while the other part of the spring is being wound upon the form A. In winding these springs, I commence at the small end, forming the shank first.

The object of my invention is to provide such improvements in machines for winding wire springs of the character shown, as to give a true tongue or centre piece, *i*, and to commence the coil so immediately at the base of this tongue *i*, as to secure a spring much more perfect in form, and one much less liable to be crushed down and its elasticity destroyed. The form of the spring is not a true cone, but is elliptical, and forms an arch at the apex, which gives much greater strength.

In the formation of this spring I commence at the apex or small end, and having secured the tongue precisely in the centre, which is readily done by the use of the couplings B and C, and thimble D, I next wind the arch, and finish at the base of the cone.

What I claim, and desire to secure by Letters Patent, is—

The couplings B and C, with the thimble D, in combination with frame A, as and for the purposes specified.

DAVID MANUEL.
